UNITED STATES PATENT OFFICE.

CHARLES D. BRANDT, OF NEW YORK, N. Y.

PUMP STIRRUP.

1,408,859.

Specification of Letters Patent.

Patented Mar. 7, 1922.

Application filed April 3, 1920. Serial No. 370,961.

To all whom it may concern:

Be it known that I, CHARLES D. BRANDT, a citizen of the United States, and a resident of Richmond Hill, borough and county of 5 Queens, city and State of New York, have invented certain new and useful Improvements in Pump Stirrups, of which the following is a specification.

My invention relates to pumps and more 10 particularly to air pumps for inflating pneumatic tires and the like and has for its object to provide a folding stirrup arrangement in which the stirrups are pivotally mounted and secured in position in a novel 15 and efficient manner and in which the necessity for drilling and drill-holes is avoided. My invention will be fully described herein- 20 after and the features of novelty will be pointed out in the appended claim.

For illustrative and descriptive purposes, 25 a specific embodiment of my invention is shown in the accompanying drawings in which Fig. 1 is an elevation; Fig. 2 is a vertical section on the line 2—2 of Fig. 1; Fig. 3 is a horizontal section on the line 3—3 of 30 Fig. 2; and Fig. 4 is an inverted plan view with the stirrups omitted.

The pump itself may be of any well known 35 and customary construction and, as shown, comprises the usual barrel 5 in which the piston is reciprocated, by means of a suitable piston rod and handle, in any recognized manner, these latter parts being omitted as unnecessary to the proper illustration of the 40 invention. The pump further is provided with the usual connection 6 for the detachable accommodation of the customary flexible hose whereby the pump is operatively connected with the pneumatic tire or other 45 element to be inflated. As is generally customary, the one end of the barrel 5 is fitted and secured in a base or cap 7 with the interior of which the connection 6 is in communication.

In the present instance this cap 7 is continued in an axial direction in the form of 50 a neck 8 which is constructed with a main recess 9 extending diametrically through said neck 8 and in an axial direction as shown in Fig. 2. Auxiliary recesses 10 extend in co-related pairs in opposite directions toward the axis of the pump at intermediate portions of said neck and communicate with the main recess 9 as shown 55 in Figs. 1 and 3. The outer ends of said auxiliary recesses 10 are open and interrupt

the periphery of said neck, while the inner ends thereof are closed, the inward length of said auxiliary recesses 10 from said periphery being predetermined as will be more 60 fully described hereinafter.

The construction further includes stirrup members 11 and 12 having foot rests 13 and toothed segments 14 arranged to mesh together, as shown in Fig. 2. The stirrup 65 members 11 and 12 are each provided with trunnions 15 arranged in diametrically opposite pairs on each stirrup member and preferably forming integral parts thereof. In the assembled condition of the parts these 70 trunnions are seated in the auxiliary recesses 10 and constitute the pivots upon which the stirrup members 11 and 12 are swung to and from their operative and inoperative positions. The stirrup members 11 75 and 12 are accommodated, in the main recess 9, which has a transverse width just sufficient to avoid interference with the pivotal movements of said members and to prevent undue vibration thereof, said foot rests 13 80 being located exteriorly of the main recess 9 as shown. The trunnions 15 are dimensioned to fit the auxiliary recesses 10 without unnecessary looseness and the inward length of the latter is such as to provide for the proper 85 meshing of the toothed segments 14, the inner ends of said auxiliary recesses 10 being located so as to constitute efficient bearings 90 for said trunnions. The means whereby the stirrup members 11 and 12 are maintained 95 in position and the trunnions 15 are held against unintentional removal from the auxiliary recesses 10, as shown in the drawings, comprise projections 16 cast or otherwise formed on the neck 8 and comprising integral extensions thereof. These extensions 100 or projections 16 are located in registry with the auxiliary recesses 10 at the outer closed ends thereof and in their initial condition occupy the positions shown in Fig. 4.

In assembling the parts the stirrup members 11 and 12 are inserted into the main recess 9 from opposite sides of the neck 8, with the trunnions 15 in registry with the auxiliary recesses 10 and moving inwardly 105 in the same, until the toothed segments 14 are in proper mesh; this operation is preferably carried out with the foot rests 13 in their operative positions.

The extensions 16 are then bent inwardly 110 at approximately right angles to their initial positions and so as to close the outer

ends of the auxiliary recesses 10 and rest against or engage the trunnions 15 as shown in Fig. 3. The latter are thus secured against unintentional removal from said auxiliary recesses 10 and yet are free to rock therein in the operative use of the pump.

The foot rests 13 and with them the stirrup members 11 and 12 may now be pivotally swung on the trunnions 15 to and from their operative and inoperative positions, the co-operation of the extensions 16 and the trunnions 15 preventing undue vibration of said stirrup members and foot rests during such movements. When the stirrup members 11 and 12 are in their operative positions, the foot rests 13 extend in opposite directions, in registry with each other and may thus be placed upon a floor, roadway or the like to provide rests for the feet whereby the pump is held in place against upward movement when in use. In the inoperative positions of the stirrup members 11 and 12 the extensions 16 lie within pockets 17 with which the stirrup members 11 and 12 are provided while the foot rests 13 extend lengthwise of the barrel 5 and close thereto so as to occupy a minimum of space and to provide a compact arrangement in the folded condition of the parts.

To dis-assemble the parts it is simply necessary to bend the extensions 16 back to the positions shown in Fig. 4 after which the trunnions 15 are free to be removed from the auxiliary recesses 10.

The invention reduces the means for maintaining the parts in operative combination to the simplest form and thus reduces the cost of production to a minimum and at the same time eliminates to a great extent the possibility of dis-arranging the parts.

The improved construction further does away with machining of the parts and avoids the necessity for drilling rivet or pin-holes thus also doing away with the use of rivets or pins which, under the strains inci-

dent to use, are likely to work loose and thereby reduce the efficiency of the pump as a mechanical structure. The recesses, main and auxiliary, are easily cut or otherwise produced in the neck, while the trunnions are readily fashioned upon the stirrup members thus reducing the selling price to a minimum and increasing the field of usefulness of the pump by making it available to a greater number of users because of its low cost.

The parts are quickly assembled and as quickly dis-assembled, whereby the cost of repairs and upkeep is maintained at a low figure.

Various changes in the form shown and described may be made within the scope of the claim without departing from the spirit of my invention.

I claim:

The combination of an air pump having a base at one end provided with an axially extending main recess and transverse auxiliary recesses arranged in co-operating pairs at opposite sides of said main recess and communicating therewith, said auxiliary recesses being open at their outer ends, stirrup-members located in said main recess and between each pair of auxiliary recesses and being movable to and from an operative position, trunnions on said stirrup-members extending into said auxiliary recesses and constituting pivots for said stirrup-members, and projections comprising integral parts of said base and extending across said auxiliary recesses and lengthwise of said trunnions to form stationary, transverse walls whereby said auxiliary recesses are outwardly closed and the trunnions are maintained in said auxiliary recesses without interference with their pivotal movements.

In testimony whereof I have hereunto set my hand.

CHARLES D. BRANDT.
